UNITED STATES PATENT OFFICE.

GEORGE E. SHIPWAY, OF NOROTON, CONNECTICUT, ASSIGNOR TO THE SALT'S TEXTILE MANUFACTURING CO., OF BRIDGEPORT, CONNECTICUT, A CORPORATION OF CONNECTICUT.

YARN-DYED FABRIC AND METHOD OF MANUFACTURING THE SAME.

Application filed September 10, 1925. Serial No. 55,533.

This invention relates to an improved yarn-dyed fabric and to the method of producing the same.

The principal object of the invention is to provide for weaving a large number of pieces of fabric, such as plush upholstery goods, to produce a maximum yardage having practically no variation in the shade or color of the goods in the different pieces.

10 A particular object of the invention is to provide a method of weaving plush or other pile fabrics from yarn dyed in different batches with the yarns from the whole number of dye lots combined so that all 15 the pieces are the average in shade of the shades in the different dye lots; the yarns being blended to give a uniform shade or color throughout the breadth and length of the fabric in each piece, and with all the 20 pieces substantially identical or uniform in shade.

Further objects of the invention are set forth in the following specification which explains a preferred practice for carrying 25 out the process and describes a particular type of fabric as an example of the goods produced by the improved method. The accompanying drawings are illustrative of 30 the character of one type of weave employed in producing the improved fabric by the method described. In the drawings:

Fig. 1 is a profile view showing the arrangement of the warp yarns in double plush weaving to which my improved 35 method is applicable;

Fig. 2 is an enlarged profile view showing the arrangement of the warp yarns in two opposite fabrics as woven double in a plush loom; and

Fig. 3 is a more or less diagrammatic view illustrating the order and arrangement of the yarns across the width of the cloth, the fabric being shown with the yarns widely separated in an open mesh to more 40 clearly illustrate their disposition and method of interlacing.

In producing plush and other pile fabrics two different systems may be employed for dyeing the goods. The cloth may be dyed 50 in the piece, or the yarn may be dyed in the

skein or cop before being woven into the goods. It is a difficult matter to obtain a uniform shade in a large number of pieces of piece-dyed goods, the shade varying with different dye-batches. That is to say, the 55 number of pieces of identical shade will be limited to the number which can be dyed in one batch, and this number is limited by the capacity of the dye-kettle. In most instances not more than six pieces can be dyed 60 in one batch and, as the pieces are approximately fifty yards in length, usually not more than three hundred yards can be dyed to a uniform shade.

Likewise, in yarn-dyeing the size of the 65 yarn batch is limited by the capacity of the dye-kettle, and hence it is well nigh impossible to produce a large number of pieces of yarn-dyed fabric having a uniform shade, the shade varying in the different pieces in 70 accordance with the different batches in which the yarn is dyed.

For some classes of goods it is not essential to produce a large number of pieces with a maximum 75 yardage of uniform shade, but for plush goods used in the upholstery arts, especially in the upholstery of automobiles, it is of utmost importance to have the different pieces of practically identical shade. In the manufacture of automobile bodies an enormous yardage of upholstery fabrics is used, and to obtain satisfactory results all 80 of the pieces must be of uniform shade. In most cases the covering for the cushions are cut from one or more pieces, and for the backs or the sides from one or more 85 different pieces, so that if the colors or shades in the different pieces do not exactly match then the result in the completed

upholstery is decidedly inharmonious and 90 unsatisfactory. Heretofore it has been the usual practice to dye upholstery goods in the piece, but as before stated, since only a limited yardage can be dyed in one batch 95 it is extremely difficult to maintain the shade uniform in the different pieces from several batches and often many pieces have to be re-dyed, and others discarded or disposed of at a loss. Moreover, in piece-dyed 100 goods there is considerable wastage of the

cloth during the dyeing process. Swatches are taken from the ends of the pieces at intervals of the dyeing to match shades or colors, and this results in a waste of considerable yardage. The ends of the pieces are also otherwise marred or defaced in the handling during the process of dyeing, and as upholstery goods of this character are relatively expensive, both in cost of raw material and manufacture, there is considerable pecuniary loss entailed with this method of production.

In producing goods by the yarn-dyed process the wastage in the piece is not so great, but the cost is higher and this method has not come into general use. However, yarn-dyed goods are considered superior to piece-dyed goods in many particulars, and this latter method of manufacturing upholstery fabrics is particularly adapted to the present improvement. As before stated, however, it has been practically impossible to obtain uniformity of shade in yarn-dyed goods, that is, to secure a minimum variation of shade in a maximum yardage of the goods. The amount of pile warp yarn which can be dyed in one batch will usually produce only five or six pieces and therefore the same disadvantages obtain as in the case with piece-dyed goods.

It is the object of the present invention to provide a method of producing yarn-dyed goods in which the yarn from different dye batches may be distributed throughout a large number of pieces, and so arranged in the individual pieces that yarns from all of the several dye lots will be perfectly blended to the eye, whereby to give not only a uniform shade in each piece, but with the shade substantially identical in an unlimited number of pieces. To this end the invention consists broadly in dyeing the yarn in a convenient number of separate batches, selecting yarns from each of the dye lots, and combining the yarns from the different dye lots in definite order and regular sequence across the warp to be woven into the goods in such manner that the shades of the yarns from the whole number of dye lots are perfectly blended to give a uniform shade in each piece and the same shade in all the pieces.

The present method of producing the improved yarn-dyed fabric is particularly advantageous in the manufacture of pile fabrics, such as plush and velvet used for upholstery goods, and Fig. 1 illustrates more or less diagrammatically a method of double plush weaving in which one fabric is superimposed above another with the pile threads floating therebetween to be cut to form the two separate pieces. In Fig. 1, L designates the lay of the loom which carries the reed R, and S, S are the two shuttles which are shot across the lay to carry the

picks of weft through the double shed. The group of harnesses is designated H, and D, D are the rollers around which the two fabrics A and B are fed as they are cut apart by the knife K. In this view the ground warp yarns g are shown opened in the two sheds a and b, while the pile warp yarns p are shown depressed in the upper shed and raised in the lower shed.

Fig. 2 is an enlarged profile or sectional view illustrative of this type of double plush weave, the ground warp yarns g, g being here shown as interlaced over and under the weft threads w in pairs in alternate order. The pile warp yarns p are also interlaced over the weft threads w in pairs, bound under single picks, and then floated across to the opposite fabric where they are again bound under single picks and interlaced over two picks, with the order repeating throughout the weave. The pile threads cross each other between the two fabrics A and B in the floats p' which, when cut by the knife K, shown in Fig. 1, are frayed or burst to intermingle their fibers in the pile which projects from the face of the cloth. It will be understood, of course, that when the weft is beaten up at the fell of the cloth all of the yarns or threads will be compacted or closed together with the pile ends or floats p' densely disposed to cover the whole face of the goods.

It is further to be understood that the present drawings are merely illustrative of one type of weave which is adaptable to my present improved method of manufacturing yarn-dyed fabrics, other weaves being susceptible of the same application so that the invention is not limited in this respect.

In carrying out the steps of the present improved process a relatively large quantity of yarn for the pile, that is the pile warp yarn, is dyed to an approximate shade in any convenient number of batches; for example, in ten dye lots, with each lot containing the maximum quantity which can be dyed in the kier or kettle at one time, usually about 250 pounds. The yarn may be dyed in the skein or on cops or packages; for instance, by the well known Franklin process, or by any other suitable method. The dyed yarn from the skeins or cops is usually wound on to spools to prepare it for delivery from a creel. All of the spools from each dye lot are grouped together and the several groups taken to the creel and placed thereon in a certain order. For example, all spools from dye lot No. 1 may be placed in one row, either vertically or horizontally, and all spools from dye lot No. 2 in an adjacent row, and so on throughout the whole ten lots. The ends from the spools in the different groups are then laid through the reed of the warping machine in regular sequence. That is, one end from

dye lot No. 1 is laid in the first dent, followed by an end from dye lot No. 2 in the second dent, then by an end from dye lot No. 3 in the third dent, and so on, with the ends from the different lots combined in sequence up to the tenth dent. A new sequence is then started by laying an end from dye lot No. 1 in the eleventh dent, an end from lot No. 2 in the twelfth dent, and so on, with the order repeating across the whole width of the reed.

The yarns are next wound onto the beam to form a warp having the required number of ends, with all of the ends disposed in definite order repeated in regular sequence in accordance with the different dye lots from which they are taken. The ends from the warp on the beam are then drawn through the reed of the loom in the same order, it being understood that in the present example these ends form the pile yarns which float between the two fabrics in weaving a double plush as shown in Fig. 1.

Fig. 3 illustrates graphically the disposition of the pile warp ends across the width of the fabric, it being understood that the yarns are shown, not in their natural close position, but spread apart at a considerable distance to more clearly illustrate their relation. Starting from the top of this view and reading down, the pile warp yarns *p* are numbered in accordance with the different dye lots from which they are selected and grouped in regular sequence. That is to say, the pile end *p* numbered 1, is taken from the first dye lot, the end designated 2 from the second dye lot, end 3 from the third lot, and so on up to 10, when the sequence is begun again with the end 1 from the first lot following the end 10 from the last lot. In the present example of the weave a pair of ground warp yarns *g*, *g* intervenes between each two pairs of pile warp yarns *p*, *p* to form the ground or body of the fabric, but these yarns do not appear on the face of the goods and need not be considered in the present discussion with respect to the color or shade of the pile.

The above described order or sequence of the pile ends is repeated many times across the width of the fabric, and it will be understood that when the yarns are laid in close juxtaposition in their natural relation in the cloth, one sequence or series of pile warp yarns from 1 to 10 with their adjacent ground warp ends will occupy a relatively narrow space with respect to the width of the fabric. That is to say, the ten ends from the ten different dye lots will usually be confined to not more than one-quarter of an inch of space across the width of the fabric, so that there will be a great many of these groups or series of the individual ends from the different dye lots in the whole fabric.

When the fabric has been treated to burst

the pile floats, that is to fray out the pile yarns, their fibers will intermingle, and where the yarns vary slightly in shade between one dye lot and the next, any such variation will not be apparent to the eye as the shades will blend evenly across the whole width of the cloth. That is to say, if the yarns vary in shade from No. 1 end to No. 10 end, for instance from light to dark, this variation will be comparatively slight, and when the ends are burst, with their fibers intermingling in the pile, their shades will be averaged. Now as the shade of any one piece of goods is the average of the shades of the yarns from ten dye lots, the pieces woven from the different series of dye lots will all be practically identical in shade, or, in other words, there will be no distinction between the shades of any two pieces in all of the goods.

It is usually not practicable to dye much more than 250 pounds of yarn in each batch and this quantity of pile warp yarn will produce above five pieces of goods of a definite yardage. With my present improved method of manufacturing the fabric, if the yarn is dyed in ten lots of 250 pounds each this quantity of yarn will make ten times five, or fifty pieces of goods. Thus it will be seen that I am enabled to get a uniform shade or color in a large number of pieces, fifty or more, which will run into a very high yardage, usually 2,500 yards or more. Moreover, as all the pieces woven from one series of dye lots are practically identical in shade with all other pieces made from other series of dye lots, the number of pieces which can be produced to the same shade is practically unlimited. It is to be understood that the number of dye lots taken as a unit in the foregoing description is arbitrarily chosen and may be varied as desired, for instance, any number from five to twenty may be used as a unit with substantially the same results.

When the material is finished each piece of goods has a uniform shade across the width and along the length of the fabric, and all of the large number of pieces produced from the several dye lots are practically uniform in shade or color; while as the process is repeated, the different pieces from subsequent multiples of dye lots will average the same in shade or color, so that great uniformity is obtained throughout continuous manufacture. It is to be understood, of course, that a certain amount of care must be taken in holding the shades of the different dye lots to a minimum variance. That is to say, all of the different batches will be dyed as closely as possible to a standard shade and will only vary from that shade in accordance with ordinary exigencies as usually encountered.

Usually the ground warp yarns and the

weft yarns are dyed to substantially match the shade of the pile yarns, but a close match and uniformity of shade in these materials is not essential as they do not show on the face of the goods. In other words, the pile gives the color to the goods and the important consideration is to obtain an unvarying shade thereof throughout continuous manufacture.

10 While I have herein explained and illustrated a particular type or pattern of weave for the cloth produced by my improved method, it will be understood that the character of the weave may be varied to a considerable extent without departing from the spirit or scope of the invention. That is to say, the present invention is concerned with the method of dyeing and arranging the dyed yarns in the fabric and not with the particular pattern or weave of the goods. Moreover, the present improved method or process may be applied to other types of fabrics besides pluses. It may also be used with other weaves than for pile fabrics, for instance for napped goods, or for other fabrics where the warp yarns form the surface of the cloth or give the color to the goods. Therefore, without limiting myself to the precise details of the method or process as herein described, or to the particular character of the fabric produced thereby, I claim:

1. An improved method of producing yarn-dyed fabrics including the following steps: dyeing a quantity of yarn to an approximate shade in separate batches; selecting an end from each of the different dye lots; arranging said ends in predetermined order in a warp; repeating the order in regular sequence across the warp; and weaving the composite warp into a fabric.

2. An improved method of manufacturing yarn-dyed fabrics including the following steps: dyeing a relatively large quantity of yarn to an approximate shade in separate batches; selecting an end from each of the dye lots; combining said ends in definite order; repeating the order in sequence to form a composite warp; and weaving the warp into a fabric to average the shades of the individual yarns whereby to obtain uniformity of shade in the goods.

3. An improved method of manufacturing yarn-dyed fabrics including the following steps: dyeing yarn to an approximate shade in separate batches; selecting an end from each of the different dye lots and arranging them in definite order in a warp; repeating the order in sequence across the warp; weaving the composite warp into a fabric; and repeating the process to average the shades of the individual yarns to produce uniformity of shade in a plurality of pieces of goods.

4. An improved method of manufacturing yarn-dyed pile fabrics including the fol-

lowing steps: dyeing yarn for the pile warp to an approximate shade in separate batches; selecting an end from each of the dye lots; combining said ends in definite order in the warp; repeating the order in sequence across the warp; and weaving the composite warp into a fabric to form the pile on the face of the goods.

5. An improved method of manufacturing yarn-dyed fabrics including the following steps: dyeing yarn to an approximate shade in separate batches; winding the dyed yarn into supplies for delivery to a warp beam; combining the ends from the supplies of the different dye lots in definite order and repeating the order in sequence; beaming the ends to form a composite warp; and weaving the warp into a fabric.

6. An improved method of manufacturing yarn-dyed fabrics including the following steps: dyeing yarn to an approximate shade in separate batches; winding the dyed yarn into supplies; selecting a supply from each dye lot and grouping them in definite order; combining the ends from the groups of supplies and beaming them in the same order repeated in sequence to form a composite warp; and weaving the warp into a fabric.

7. An improved method of manufacturing yarn-dyed fabrics including the following steps: dyeing a quantity of yarn to an approximate shade in separate batches; spooling the yarn for delivery from a creel; selecting a spool from each dye lot and grouping them on the creel; laying the ends from the spools in definite order in the reed in accordance with the grouping of the spools; repeating the order in regular sequence across the reed; beaming the ends in the order laid in the reed to form a warp; and weaving the warp into a fabric.

8. An improved method of manufacturing yarn-dyed fabrics including the following steps: dyeing a quantity of yarn to an approximate shade in a number of separate batches; spooling the yarn and grouping the spools with an end from each dye lot in each group; beaming the yarn from the spools with the ends from each group arranged in definite order and repeated in sequence across the warp; and weaving the warp into a fabric.

9. As a new article of manufacture, a fabric comprising warp yarns dyed to the same color but varying slightly in shade as dyed in different batches, said fabric having the warp yarns combined in the weave with a yarn from one batch arranged adjacent a 125 yarn from another batch in certain order across the cloth whereby the shades of all the yarns from the different batches are averaged to secure a uniform shade throughout the goods.

10. An improved yarn-dyed pile fabric comprising pile warp yarns dyed to the same color but varying slightly in shade as dyed in different batches, said fabric having 10
5 the pile warp yarns arranged in series with a yarn of one shade from a certain batch adjacent that of another shade from a dif- ferent batch and the series repeated across the cloth whereby the different shades are averaged to produce uniformity of shade throughout the goods.

In testimony whereof I affix my signature.

GEORGE E. SHIPWAY.
